US00D419537S

United States Patent [19] Rodriguez

[11] Patent Number: Des. 419,537
[45] Date of Patent: ** Jan. 25, 2000

[54] APPARATUS FOR RECORDING AND/OR
REPRODUCING DIGITAL DATA

[75] Inventor: **Gustavo A Rodriguez**, Eindhoven,
Netherlands

[73] Assignee: **U.S. Philips Corporation**, New York,
N.Y.

[**] Term: **14 Years**

[21] Appl. No.: **29/095,565**

[22] Filed: **Oct. 26, 1998**

[30] Foreign Application Priority Data

May 13, 1998 [WO] WIPO DMA/004100

[51] LOC (7) Cl. **14-02**

[52] U.S. Cl. **D14/107**

[57] CLAIM

The ornamental design for an apparatus for recording and/or
reproducing digital data, as shown and described.

DESCRIPTION

FIG. 1 is a front elevational view of an apparatus for
recording and/or reproducing digital data showing my new
design;

FIG. 2 is a rear elevational view thereof;

FIG. 3 is a right side elevational view thereof;

FIG. 4 is a left side elevational view thereof;

FIG. 5 is a top plan view thereof; and,

FIG. 6 is a bottom plan view thereof.
